UNITED STATES PATENT OFFICE.

GEORGE G. STOUT, OF PARKERSBURG, WEST VIRGINIA.

SWITCH.

1,005,899.

Specification of Letters Patent. Patented Oct. 17, 1911.

Application filed September 26, 1907. Serial No. 394,696.

To all whom it may concern:

Be it known that I, GEORGE G. STOUT, a citizen of the United States, residing at Parkersburg, in the county of Wood and State of West Virginia, have invented certain new and useful Improvements in Switches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to electric switches and has for its object to provide a switch for closing an electric circuit by an independent circuit, such as for instance an arc circuit, in such manner that an independent 20 electric circuit can be closed by an arc or other circuit for the purpose of lighting alleys, streets, road-ways and the like.

With this object in view my invention consists in the novel construction of the 25 switch and also in certain combinations of parts all of which will be first fully described and afterward specifically pointed out in the appended claims.

Referring to the accompanying drawing: 30 Figure 1 is a vertical sectional view taken through the coil or solenoid showing switch also in section. Fig. 2 is a diagrammatic view showing the winding of the coil or solenoid. Fig. 3 is an elevation showing the coil and 35 switch and illustrating the casing or covering in vertical section. Fig. 4 is a top plan view of one of the blades of the switch. Fig. 5 is a top plan view showing a switch having two blades. Fig. 6 is an end view of 40 one of the switch blades and hinged connection, and, Fig. 7 is an end view of the flexibly held contact plate.

Like numerals of reference indicate the same parts throughout the several figures 45 in which:

1 indicates a plate or wall constructed preferably of iron forming a base for the entire device, said plate or wall being provided with a slot 2 through which a bolt 3 50 passes and a perforation 4 through which a similar bolt 5 passes.

6 indicates the hood or cover which may be constructed of any suitable material and of a form as shown in Fig. 1, in order to 55 protect the device when the same is used out of doors.

7 indicates the coil or solenoid which has a double winding as shown in the diagrammatic view, Fig. 2. Within the coil or solenoid 7 I provide a fixed magnet 8 which is 60 constructed preferably of sheets or layers of soft iron, and within the core of the coil I provide a movable magnet 9 having an extending rod 10 which passes out of the core and has its end connected to the switch 65 11 as shown in Figs. 1 and 3. The switch 11 can be constructed as shown in Figs. 1 and 3, or it may be constructed as shown in Fig. 5, in which instance the rod 10 is connected to an insulated bar 12 which connects 70 the arms or blades 13 of the switch 11.

The coil or solenoid 7 is preferably supported on a bracket 14 having a guide plate 15 at the top thereof in order to securely hold the coil in position. The bracket 14 75 is provided with two depending arms 16 to which is secured a base plate 17 of slate or other insulated material. Secured to the base plate 17 is the switch 11, each arm or blade of the switch being connected to the 80 hinged member 18 as shown in Figs. 4 and 6, said hinged member 18 being securely screwed or bolted to the base plate 17 as shown in Fig. 1, one of the bolts 19 serving as a binding post to which is connected one 85 of the wires 20.

Arranged under the base plate 17 is a plate 21 securely bolted or screwed thereto, and a slot or opening 22 is provided in said 90 plate 21.

23 indicates a contact plate secured to two vertical posts or bars 24, each of said posts or bars being provided with an enlarged head 25 and having a coil spring 26 of compression strain which normally holds 95 said plate in position shown in Fig. 1. A flexible connection 27 passing from the plate 23 to the plate 21 insures a good contact and prevents arcing. The wire 28 of the independent circuit is connected to the plate 21 100 preferably by means of a bolt or screw 29.

The rod or bar 10 of the movable magnet 9 passes through the base plate 17 and is provided with an adjustable collar 30 which is provided on said bar or rod 10 to limit the downward movement of the movable magnet 9.

As shown in Figs. 1 and 3 a flexible connection is provided between the arms or blades 13 of the switch and the hinged member 18 in order to secure a good contact to prevent arcing. The arms or blades 13 of 110

the switch 11 are given a quarter turn in order to present a flat surface to accommodate a spring contact piece 31 as shown in the drawings.

- 5 Having thus described the several parts of my invention its operation is as follows: The arc or other circuit passes through the coil or solenoid 7 energizing the fixed magnet 8 thus drawing the movable magnet 9 toward the fixed magnet 8. This movement of the movable magnet 9 is communicated by means of the bar or rod 10 to the switch 11 drawing the switch in an upward direction and causing the spring contact 31 on 10 the arms or blades 13 of the switch 11 to be brought in contact with the contact plate 23. The circuit then passes through the arms or blades of the switch, through the contact plate 23, flexible connection 27 and plate 21, 15 thus closing the independent circuit which is wired as shown at 20 and 28.

Any variation in the arc or other circuit which passes through the coil or solenoid 7 will of course vary or alter the height or 20 position of the movable magnet 9 within the core of the coil or solenoid. As a matter of fact there is a sudden variation which causes an oscillating or vibrating movement of the movable magnet 9. Should this oscillating or vibrating movement be communicated to the switch of usual construction considerable noise and rattling would result. By the construction just described, however, this oscillating or vibrating movement of 25 the movable magnet 9 is taken care of by the spring held contact plate 23 and the spring contact 31 on the switch arms or blades 13, said spring contact 31 oscillating over the surface of the contact plate 23 and 30 wiping the same upon oscillatory movement of the magnet and switch. The extent of movement being clearly shown in dotted lines in Fig. 3, thus providing a flexible or resilient switch which can be actuated by an 35 independent circuit without any attendant rattling or noises.

Having thus fully described my invention what I claim as new and desire to secure by Letters Patent of the United States, is:

1. A switch of the character described 50 comprising a solenoid having therein a fixed magnet and a movable magnet, a base plate under said solenoid, a pivoted switch arm associated with said base plate, a resiliently held contact plate under said base plate, a spring contact on said switch arm adapted to engage the said resiliently held contact plate, means for connecting said movable magnet with said switch arm to communicate the movement of said movable magnet 55 to said switch arm, said resiliently held contact plate being arranged in the path of movement of the spring contact on the switch arm in such manner as to be engaged and wiped by the same, the spring contact 60 on said switch arm being resilient and wiping over the face of the said resiliently held contact plate upon movement of the said switch arm controlled by the said movable magnet within the said solenoid. 70

2. A switch of the character described, comprising a coil or solenoid having therein a fixed magnet and a movable magnet, a base plate of insulating material under said coil, a plate of conducting material on said base plate, a resiliently held contact plate carried by said plate of conducting material, a switch arm under said resiliently held contact plate, a spring contact carried on said switch arm, a connection between 75 said movable magnet and said switch arm for communicating the movement of said movable magnet to said switch arm to raise said spring contact thereon into engagement with said resiliently held contact plate, substantially as described. 80

In testimony whereof, I affix my signature, in presence of two witnesses.

GEORGE G. STOUT.
